UNITED STATES PATENT OFFICE.

DAVID W. HAWKSWORTH, OF DETROIT, MICHIGAN, ASSIGNOR TO HUTCHINS CAR ROOFING COMPANY, OF DETROIT, MICHIGAN, A CORPORATION OF MICHIGAN.

CAR-ROOF.

1,101,848.

Specification of Letters Patent. Patented June 30, 1914.

Application filed August 29, 1910. Serial No. 579,553.

To all whom it may concern:

Be it known that I, DAVID W. HAWKSWORTH, a citizen of the United States of America, residing at Detroit, in the county 5 of Wayne and State of Michigan, have invented certain new and useful Improvements in Car-Roofs, of which the following is a specification, reference being had therein to the accompanying drawings.

10 The invention relates to car roofs of the type in which metallic roofing sheets are employed said sheets being secured by depending flanges at the eaves.

It is the object of the invention to avoid 15 the rupture of the sheets due to torsional or weaving stresses in the roof frame by providing freedom of adjustment.

To this end the invention consists in the construction as hereinafter set forth.

20 In the drawings, Figure 1 is a sectional perspective view of a portion of the roof structure embodying my invention; Fig. 2 is a cross section through the plate and fascia of a car showing the manner of attaching the roof; Fig. 3 is an enlarged cross section showing a modified construction.

It is usual in the construction of car roofs of the type above referred to, to nail the depending flanges of the roof sheets to the 30 fascia of the car. This holds each roofing plate in a fixed relation to the side of the car, and as there is frequently a relative movement between said side and the roof frame the sheets are thereby subjected to 35 stresses. With my improved construction the depending flanges of the sheets are not nailed but are held by means which while preventing any vertical or longitudinal displacement of the sheet, still provide freedom of lateral adjustment and compensate 40 for any weaving stresses in the roof frame.

In detail A is the side plate of a car, B is the sheeting and C is the fascia, all of usual and standard construction.

45 D is the roofing sheet which is provided at the eaves with a depending flange E. This flange is however, normally spaced from the outer surface of the fascia and is secured to the latter by means providing a 50 free inward play of the flange. The securing means preferably employed consists of bolts F which pass through the fascia and plate and also through aligned apertures in the flange E. These bolts are provided 55 with heads G which are permanently spaced

from the fascia by a sleeve or thimble H. The apertures in the flange E are of sufficient size to slidably engage the thimbles H while the flange is limited as to outward movement by the head G. If however, any 60 stresses develop which tend to draw one side or the other of the sheet inward it is free to move upon the sleeve H and find its proper position of adjustment without any injurious stresses upon the metal of the plate. 65 As shown, three bolts F are used for each of the sheets D and intermediate the sheets bolts having similar spacing thimbles are used for securing the carline cap I. Thus, in operation a high degree of flexibility is 70 imparted to the roof, while the normal spacing of the flanges E from the fascia is also advantageous in that it prevents accumulation of moisture.

In Fig. 3 a modified construction is shown 75 in which the bolt F' is formed with a shoulder F² for bearing against the fascia. This separates the head G from the fascia in the same manner as by use of the thimble.

What I claim as my invention is:

1. In a car roof, the combination with the side plate and fascia of a roofing plate having a depending flange overlapping said fascia with an air space normally therebetween, a bolt for securing said flange to said 80 fascia, a thimble on said bolt forming a spacer, and a flange on the inner end of said thimble for limiting the inward movement of the sheet flange.

2. In a car roof, the combination with the side plate and fascia, of a roofing sheet having a depending flange overlapping said fascia and normally spaced therefrom, a bolt for securing said fascia to the side plate, said bolt having an extension engaging an 90 aperture in the depending flange and a headed portion for preventing outward movement of said flange, and a thimble engaging said bolt intermediate its headed portion and said fascia, said thimble having a portion of lesser diameter than the aperture in the sheet and a portion of greater diameter than the aperture, for preventing contact of the flange with the fascia. 100

In testimony whereof I affix my signature 105 in presence of two witnesses.

DAVID W. HAWKSWORTH.
